UNITED STATES PATENT OFFICE.

JOSEPH C. THOMAS, OF AKRON, OHIO.

DISPLAY APPARATUS.

Application filed November 13, 1922. Serial No. 600,618.

To all whom it may concern:

Be it known that I, JOSEPH C. THOMAS, a citizen of the United States, residing at Akron, in the county of Summit and State 5 of Ohio, have invented a new and useful Display Apparatus, of which the following is a specification.

My invention relates to apparatus for displaying signals or signs or both.

10 The object of my invention is a simple and efficient apparatus adapted to display letters, or numerals, or other symbols and a danger signal.

I attain this object by the apparatus shown 15 in the accompanying drawing which illustrates my invention as at present preferred, and in which Fig. 1 is a perspective view of a display apparatus, embodying the features of my invention, and showing such apparatus provided with letters comprising the name of the town, "Akron" and with a danger signal; Fig. 2 is a section on line 2—2 of Fig. 1. Fig. 3 is a section on line 3—3 of Fig. 1; and Fig. 4 is a perspective 25 view of a portion of a modified display apparatus, one end being broken away to show the cross section thereof.

Similar reference characters refer to similar parts throughout the views.

30 The present invention is illustrated as applied to vehicles which display a license number plate and a danger signal.

It is now quite prevalent to also display the name of the town in which the vehicle 35 owner lives, or his name, or other identifying symbols, in connection with the usual license number or with the usual danger signal.

The present invention embodies means 40 whereby either all or any number of the above features may be embodied in a single apparatus.

Referring now particularly to the drawings,

45 The case A, Figs. 1, 2 and 3 in this instance, is made in one piece, preferably of aluminum or of other material adapted for the purpose appearing presently.

This case A has the opening 10 in its 50 bottom, the rear wall 11 provided with the boss 12, the top wall 13, and the front wall 14. The lugs 15 are formed on the lower end of the wall 11, are offset from the back of the case to permit the bottom thereof to rest on the shoulder 16 provided on the up-

per edge of the bracket 20, and each of these lugs 15 is provided with the slot 17 adapted to permit the passage therethrough of the bolts 18 which, in this instance, secure the license number plate 19 as well as the display apparatus to the license number bracket 20 usually found on vehicles.

It is noted that the weight of the display apparatus, as well as the usual shocks or other vibrations, is borne by the shoulders 16 so that the bolts 18 are relieved of as much load as possible; thereby preventing the same to become loose and probably lose the apparatus as well as the license plate.

The bead 21 is formed on the front wall 14 to stiffen this wall at the bottom and for ornamentation.

In the present instance, the wall 14 has the symbol openings 22 therethrough formed as letters representing the word "Akron" 75 and also has the danger signal openings 23 therethrough as seen in Fig. 1.

On the inside, this wall 14 has the bead 24 adapted to retain the transparent member 25 in position.

In the present instance, the member 25 is made of red colored glass and is held to the inside of the wall 14 and within the beads 24 by the screws 26 and the washers 27. The gaskets 28 and 29 may be introduced to prevent breakage of the glass 25.

The inside of the lower end of the wall 14 is curved inward to reflect the light rays thrown thereon downward and backward against the number plate 19 to illuminate the same.

The lamp socket 30 is slidably mounted in the boss 12, is longitudinally adjustable therein, and is held in adjusted position by the screw 31.

The lamp 32 is mounted in the socket 30 and is connected to a source of current by means of the lead 33.

The reflector B is mounted in the case A and is, preferably, of parabolic formation as far as such formation can be applied to a reflector having an irregular surface.

This reflector B has the central portion 34 and the end portions 35. The curvature of the portion 34 is formed to direct one portion of the light rays from the lamp 32 toward the danger signal openings 23. The curvature of each of the portions 35 is formed to direct the other portion of the light rays forward toward the letter open-

ings 22 and also downward toward the number plate 19.

The apparatus described operates either in day time or at night. In the day time, when the lamp 32 does not illuminate, there usually is sufficient sun-light striking the red glass, through the openings in the front wall, to show a red reflection in contrast to the white surface (body made of aluminum as previously stated) and thereby render the symbols in the front of the case easily discernible. At night when the lamp 32 is illuminating, some of the light rays of the lamp 32, aided by the portion 34 of the reflector, illumine the danger signal openings 23 and thereby show the danger signal as a bright red light on a white background; other light rays of the lamp 32, aided by the portions 35 of the reflector, illumine the letter openings 22 and show these letters in red on a white background and also illumine the number plate 19 with a white light.

A modified apparatus is shown in Fig. 4. This apparatus has the case C and the cover D.

The case C has the rear wall 36 which is curved, both vertically and horizontally, preferably of parabolic curvatures, and also has the lugs 37 similar to and for the same purpose as the lugs 15, and also has the boss 38 projecting outside of the case only, so that the inside thereof may be polished readily. The front of the case is open and has the flange 39.

The lamp socket 40 is mounted in the boss 38 and the lamp 41 is mounted in the lamp socket 40.

The cover D, preferably made of aluminum or other material for the purpose previously described, is secured to the case C by means of the screws 42 and has the shoulders 43 on the inner face thereof to retain the transparent member 44 which is similar to the member 25 previously described and which is secured to the cover D in a manner similar to that previously described.

The cover D, in this instance, has symbols in the form of letters 45 comprising the word "Akron," as well as symbols in the form of numerals 46 comprising the license number as well as the danger signal openings 47 cut therethrough.

In this instance, the inside of the case C may be polished to act as a reflector which polishing is facilitated by the open front of the case and by the elimination of all bosses or projections on the inside of the case.

The operation of this modification is similar to the apparatus previously described.

It will be seen that the present invention provides a simple and efficient means for displaying a signal or other sign easily discernible either in the dark or in daylight.

In either of the apparatuses shown, the transparent member may be omitted in which case the light from the lamps shines directly through the openings and the letters appear in white; this arrangement, however, is not well adapted for signals or signs displayed at day time and does not show the usual red danger signal unless a red glass is provided over the danger signal openings.

Having described my invention and without limiting myself to the precise construction shown and described,

I claim:

1. A display apparatus comprising, a case having opaque walls and an opening in the bottom wall thereof, a sign plate on the front wall of said case, a license plate on the bottom of said case adjacent said opening, a concave reflector in said case and the front edges thereof extending substantially to said transparent plate except a portion of the lower wall thereof which portion is curved downward and extends substantially to said opening in the bottom of the case, a lamp in the hollow of said reflector to illumine said sign plate and said license plate through said opening.

2. In combination, a bracket adapted to be secured to a support, a sign secured to said bracket, said bracket being provided with a shoulder along its upper edge, a display apparatus resting on said shoulder and having lugs extending downward and bearing against said bracket, bolts passing through said lugs and said sign and said bracket, and means for displaying symbols and signals from said apparatus and for illuminating said sign.

3. In combination, a bracket adapted to be secured to a support, a sign secured to said bracket, said bracket being provided with a shoulder along its upper edge, a display apparatus resting on said shoulder and having lugs extending downward and bearing against said bracket, bolts passing through said lugs and said sign and said bracket, means for displaying symbols and signals from said apparatus, a lamp in said apparatus, and a reflector in said apparatus adapted to direct light rays from said lamp forward and downward.

JOSEPH C. THOMAS.
